[57] **CLAIM**

The ornamental design for a 4-sided display, as shown and described.

DESCRIPTION

FIG. 1 is a top, front, and right side perspective view of a first embodiment a 4-sided display showing my new design;

FIG. 2 is a front elevational view;

FIG. 3 is a top plan view;

FIG. 4 is a left side elevational view;

FIG. 5 is a right side elevational view;

FIG. 6 is a rear elevational view;

FIG. 7 is a top, front, and right side view of a second embodiment of that shown in FIG. 1. This view has the same appearance as the top, rear, and left side perspective view of both the first and second embodiments;

FIG. 8 is a top plan view of the second embodiment;

FIG. 9 is a front elevational view;

FIG. 10 is a left side elevational view;

FIG. 11 is a right side elevational view; and,

FIG. 12 is a rear elevational view thereof.
